United States Patent Office

Des. 187,326
Patented Mar. 1, 1960

187,326

BELT BUCKLE

William Geiser, Monrovia, Calif.

Application August 27, 1959, Serial No. 57,329

Term of patent 7 years

(Cl. D17—1)

Fig. 1.

Fig. 2.

Fig. 1 is a front elevation of a belt buckle, showing my new design; and

Fig. 2 is a top edge view of the belt buckle of Fig. 1.

I claim:

The ornamental design for a belt buckle, substantially as shown.
